UNITED STATES PATENT OFFICE.

HENRY E. POND, OF FRANKLIN, MASSACHUSETTS, ASSIGNOR TO JAMES H. NASON, OF SAME PLACE.

GAME APPARATUS.

SPECIFICATION forming part of Letters Patent No. 259,207, dated June 6, 1882.

Application filed April 1, 1882. (No model.)

To all whom it may concern:

Be it known that I, HENRY E. POND, of Franklin, county of Norfolk, State of Massachusetts, have invented an Improvement in 5 Game Apparatus, of which the following description, in connection with the accompanying drawings, is a specification.

My invention relates to a game apparatus, and has for its object to include in a single 10 convenient compact apparatus means for playing several different games of skill and chance.

The apparatus is shown as consisting of a box, which, when closed, contains all the necessary apparatus for playing the different games, 15 and has marked or inlaid upon one of its outer surfaces the points constituting a backgammon-board, the said box including in its movable apparatus the checkers, dice, and dice-boxes needful for playing backgammon. The 20 opposite face of the said box has marked in one diagram the square of an ordinary checker or chess board, and also the diagram of the game known as "morris" or "fox and geese." The two portions of the box are hinged together, and when opened form an alley which 25 is provided with spots for ten-pins, and is also provided with a removable bridge and pockets for playing the game of sipio. A small spring-gun is employed to shoot or propel 30 balls at the ten-pins, or at the stationary ball employed in the game of sipio. All the movable apparatus—such as the balls, ten-pins, checkers, and dice—can be contained within a small 35 box provided for the purpose, it being held in place in the main box or the game apparatus by a suitable brace, the said main box being closed by a clasp, so that it can be readily carried about without danger of losing any of its contents.

40 Figure 1 is a perspective view of the apparatus closed, showing the diagrams of two of the games; Fig. 2, a similar view, showing the opposite side of the box with backgammon-board diagram thereon; Fig. 3, a view of the interior of the box arranged for the game of sipio; Fig. 4, a similar view thereof, arranged for ten-pins; Fig. 5, a plan view of the box when closed, showing the movable apparatus in the interior thereof; and Fig. 6, a

longitudinal section of the gun employed for 50 propelling the balls.

The apparatus consists mainly of a box made in two portions, *a b*, hinged together at *c*, the said portions, when turned over upon one another, as shown in Figs. 1 and 2, being held 55 together by a clasp, and then forming a rectangular box, one of the sides of which is shown in Fig. 1 as provided with a diagram, *e*, for the game of morris or fox and geese, and diagram *f* for checkers, while the other side 60 is marked out for the game of backgammon, as shown in Fig. 2.

When the two portions of the box are turned upon the hinges *c* into line with one another, as shown in Figs. 3 and 4, they form a long 65 trough, having an alley, *g*, provided at one end with a spring-gun, *h*, for propelling a ball along the said alley.

The portion *a* of the box is provided with 70 grooves 2 for a bridge, *i*, (see Fig. 3,) having a series of different openings or arches, toward which a ball, *j*, mounted upon a spot near the middle of the alley, may be propelled, it being struck by the ball *k*, (see Fig. 6,) thrown from the gun *h*.

A series of pockets, *l*, located behind the bridge *i*, receive the balls in case they pass through the arches, and thus indicate which arch the ball came through, different numbers being scored for sending a ball through 80 different arches.

The end of the alley *g* in the portion *a* of the apparatus is provided with spots for ten-pins *m*, (see Fig. 4,) which may be shot at by a ball 85 propelled directly from the gun *h* or by a ball mounted upon the spot, as at *j*, (see Fig. 3,) and propelled by impact from the ball shot from the gun.

When using the apparatus for ten-pins, as shown in Fig. 4, the bridge *i* is removed 90 from the grooves.

The gun *h* is provided with a pivot, *n*, as shown in Fig. 6, mounted in a socket in the end of the alley *g*, the ends of the said gun resting upon arcs *o*, and being held in place by 95 an elastic strap, *p*, permanently attached to the alley *g*, and passing over a projection, *q*, near the muzzle of the gun, thus enabling the

gun to be turned and held in any desired direction while the ball is being fired. The said gun has a chamber, r , in its muzzle portion of sufficient size to receive the ball k , as shown in Fig. 6, and also has a plunger, s , connected with the movable breech-piece t , drawn by an elastic spring, u , (see Figs. 3 and 4,) toward the body of the gun. The said breech-piece t has connected with it a holding-rod, v , which is engaged by the trigger w to hold the said breech-piece back, with the spring u strained, as shown in Fig. 3, and dotted lines Fig. 6. By pressing on the end w' of the said trigger the rod v is released, when the said breech-piece t and plunger s are propelled forward and strike the ball k , which is then at the back of the chamber r , thus propelling the said ball forward.

The small detachable portions of the apparatus—such as the balls j k , ten-pins m , dice, checker or chess men y —are inclosed in a box, z , (see Fig. 5,) having suitable partitions, and the portion a of the main outside box or apparatus is provided with a removable brace, a^2 , fitted in slots 3, for retaining the said interior box, z , in proper position.

In packing up the apparatus, as shown in Fig. 5, the bridge i and braces a^2 are inserted in their respective slots 2 3, and the box z and its contents placed between the said bridge and brace. A sufficient space is left at the side of the said box z for the dice-boxes c^3 and gun h , which may be partly inserted in one of the said dice-boxes. When packed in this way the apparatus can be carried in any position without danger of losing any of the small articles or of having them rattle about.

I claim—

1. In a game apparatus, the main box or case, consisting of two portions, a b , adapted, when opened, to form an alley, and having their sides marked with diagrams, as described, for different games, in combination with a box for containing the removable devices employed in the games, and means to secure the same in the interior of the main box or case when closed, substantially as described. 45

2. The main box, consisting of two portions hinged together, and provided on its outside with diagrams of games to be played thereon when closed, and adapted, when opened, to form an alley, combined with removable bridge-piece i , pockets l , and the spring-gun h , substantially as described. 50

3. The alley g , provided with the pivotal 55 socket, combined with the segments and elastic band p , and the spring-gun, adapted to be held pointing in any desired direction by the said band, substantially as described.

4. In a game apparatus, the ball-propelling 60 gun, it consisting of the main chambered portion or barrel of the gun, with the plunger, breech-piece, and spring, and the guide-rod v , connected with the said breech-piece, and trigger, adapted to engage the said guide-rod, substantially as described. 65

In testimony whereof I have signed my name to this specification in the presence of two subscribing witnesses.

HENRY E. POND.
